SCREEN TYPE SEPARATOR

Walter G. Glascoff, Waupun, Wis., assignor to Berlin Chapman Company, Berlin, Wis., a corporation of Wisconsin

Application September 30, 1953, Serial No. 383,177

2 Claims. (Cl. 209—315)

The present invention relates generally to improvements in the art of sorting and grading materials of diverse sizes, and relates more particularly to improvements in separating apparatus of the screen type.

A primary object of the present invention is to provide an improved screen type separator especially adapted for sorting and grading vegetables such as peas or the like which is extremely compact and durable in construction and highly efficient and economical in use.

Although it has heretofore been proposed to utilize devices embodying a spaced series of superimposed vibratory screens of differently sized meshes for separating diverse materials, none of these prior assemblages has proven completely satisfactory in sorting and grading relatively perishable and soft-bodied products such as peas and corn which are subject to considerable crushing and mashing and consequent loss of product. Most of these prior separators are undesirably bulky, complicated and expensive, and therefore require considerable floor space as well as expert and costly maintenance. Furthermore, many of these prior devices handle the mass product in an exceedingly rough manner thereby causing excessive damage and loss of product by bruising and mashing.

It is therefore a more specific object of my present invention to provide an improved apparatus for sorting and grading perishable products which obviates the disadvantages and objections heretofore attendant similar devices.

Another specific object of this invention is to provide an improved pea grader which requires a minimum amount of floor space and which is adapted to sort and grade a maximum quantity of peas in a given period of time.

Another specific object of the invention is to provide an improved pea grading machine which is adapted to most effectively and gently sort the product as to different sizes with a minimum resultant mechanical damage to the product.

Still another specific object of my present invention is to provide an improved unitary and relatively portable screen type separator which comprises exceedingly few parts which are all readily accessible for periodic cleaning, replacement or repair.

A further specific object of the present invention is to provide an improved pea grader embodying reciprocating screens which may be readily interchanged as to mesh size so as to provide utmost flexibility in its adaptations.

An additional specific object of the present invention is to provide an improved separating device comprising, a main frame, a series of superimposed inclined screens of different mesh sizes suspended from the frame for oscillatory movement in the direction of inclination, means for supplying batches of material to be separated as to size to the upper end of the top screen, means for reciprocating the screens to cause oscillation thereof in their direction of inclination, a resilient wiper blade

2

for each of the screens coating directly with the bottom surface thereof throughout the direction of inclination, and means for reciprocating the wiper blades in a direction transverse to the direction of movement of the screens.

These and other objects and advantages of the invention will be apparent from the following detailed description.

A clear conception of the several features constituting the present improvement and of the mode of constructing 10 and of utilizing a typical pea grader embodying the invention may be had by referring to the drawing accompanying and forming a part of this specification, wherein like reference characters designate the same or similar parts in the several views.

Fig. 1 is a side view of one of my improved separators with portions of the screen and wiper frames being broken away to reveal normally concealed structure;

Fig. 2 is an end view of the device with portions of the screen frames again being broken away for the sake of 20 clarity; and

Fig. 3 is a diagrammatic fragmentary perspective view of one of the screens and its associated wiper mechanism.

While the invention has been shown and described herein as being especially embodied in a pea sorting and 25 grading device having a certain number or superimposed grading screens disposed at a particular angle, it is not desired or intended to thereby unnecessarily restrict the scope or utility of the improvement; and it is also contemplated that certain specific descriptive terms used 30 herein shall be given the broadest possible interpretation consistent with the disclosure.

Referring to the drawing, the typical improved separating unit shown therein comprises, in general, a substantially open main frame 5 formed of angle irons or the like; a series of superimposed inclined and normally parallel flat screens 6 of different mesh sizes suspended at opposite ends from the frame 5 in vertically spaced relationship for oscillatory movement in the direction of inclination as by means of rocker arms 7, 8 carried by 40 horizontal rocker shafts 9, 10 respectively mounted at different elevations at the ends of the frame 5; means such as a hopper 11 for supplying batches of peas or other material to be separated as to size to the upper or elevated end of the top screen; common means such as a vertical drive shaft 12 journaled on one end of the frame 5 and having a spaced series of eccentrics 13 each connected to the elevated end of one of the screens 6 by a connecting rod or link 14 for simultaneously reciprocating all of the screens to thereby cause oscillation 45 thereof in their direction of inclination, the shaft 12 being suitably driven by means of a motor 15 or the like also mounted on the frame 5; one or more resilient wiper blades 16 for each of the screens 6 coating directly with the bottom surface thereof, the respective sets of wiper blades 16 being longitudinally inclined similarly to the respective screens 6 so as to contact the same throughout the direction of inclination thereof and being carried by suitable frames 17 slidably supported for reciprocating motion on rods 18, 19 extending transversely across the main frame 5; and common means such as a vertically extending eccentric or cam shaft 20 mounted for rotation on a side of the frame 5 and connected with the respective wiper frames 17 by a series of arms 21 for simultaneously reciprocating all of the wiper blades 16 in a direction transverse or perpendicular to the direction of movement of the screens 6, the cam shaft 20 being also driven by suitable means such as a motor 22 mounted on the frame 5 or through a reduction gear or drive arrangement by the motor 15.

As indicated, the screens 6 should be of variable sized mesh with the screen having the largest mesh openings

being at the top and each successive lower screen being of progressively smaller size mesh, and each of these screens may be suitably supported and retained in flat condition within a rectangular frame 23 formed of angle irons or the like. For receiving the graded material which gravitates down the successive inclined screens 6 during oscillation thereof, a suitable spout or trough, not shown, may be positioned immediately under the lower end of each screen; and if desired, a pan or hopper 24 may be provided immediately below the lowermost screen for receiving the fine material, water or the like which gravitates therethrough. The drive shaft 12 may be conveniently journaled at opposite ends in suitable bearings carried by brackets 25, 26 which are rigidly secured to the frame 5 at the end adjacent to the elevated portions of the screens, and the motor for driving the shaft 12 through a suitable belt and sprocket drive 27 may be most conveniently rigidly mounted by means of a bracket 28 to the frame adjacent to the lower end of the shaft 12 to thereby provide a unitary assemblage. Likewise, the shaft 20 may be eccentrically mounted on upper and lower stub shafts 29, 30 respectively which are journaled in bearing brackets 31, 32 respectively for rotation by the motor 22 which may be rigidly mounted on a lower brace 33 of the frame 5 and coupled to the shaft 30 in any suitable known manner for low speed operation. The wiper blades 16 may be formed of any suitable resilient material such as rubber with each carrier or frame member 17 being formed with a plurality of transversely spaced blades so as to reduce the stroke necessary to reciprocate the blades transversely across the entire area of the screen, and each blade carrier 17 is preferably so positioned with respect to the adjacent upper screen 6 as to place the respective set of blades 16 under resilient pressure against the bottom surface of the screen to assure an effective wiping action at all times.

In operation, a batch of peas or other material to be separated according to size is supplied to the elevated end of the upper screen through the hopper 11. As the screens 6 are simultaneously oscillated on the rockers 7, 8 through their eccentric connections with the motor driven shaft 12, the peas are caused to spread out in a relatively thin sheet over the surface of the upper screen and to gravitate toward the lower end of the inclined screen with the smaller sized peas falling through the relatively large screen openings onto the next succeeding lower screen of smaller mesh size where the separating or grading process is continued. As the peas are thus graded according to size by each successive screen 6 of smaller mesh size, the graded peas are caught in separate pans or troughs, not shown, which may be placed immediately below and adjacent to the lower end of each inclined screen; and the fines as well as any water or minute dirt particles gravitate through the lowermost screen 6 into the pan 24. Since some of the peas which are not quite small enough to gravitate therethrough may become partially lodged or seated within the mesh openings of the successive screens despite the oscillatory motion thereof, the wiper blades 16 are provided to dislodge the peas from the openings and thereby prevent clogging of the screens; and these wiper blades carried by the reciprocating frames 17 bear against the lower surface of the respective screens under slight pressure so as to gently push the peas upwardly out of the screen openings as the blades are reciprocated transversely across the screens perpendicularly to their movement by means of the motor driven cam shaft 20.

From the foregoing detailed description, it is believed apparent that the improved separating or grading apparatus provides a unitary structure which is highly efficient and which may be produced and operated at low cost to the consumer. The screens 6 may, of course, be interchanged if desired with screens of smaller or larger mesh openings, and any number of screens may be utilized dependent upon the number of grades or sizes into which

it is desired to separate the batch. The main frame 5 as well as the screen frames 23 may be formed of suitable angle irons, and since it is necessary to provide an open carrier or frame member for the wiper blades 16 to permit the graded material to fall unto the next successive lower screen, the wiper blade frame 17 may be conveniently formed of a rectangular open member provided with a series of spaced cross pieces 34 secured to the sides of the rectangular frame and receiving and supporting the wiper blades. The improved units have proven highly successful in actual use and have been found to increase the capacity of canning factories by reason of their efficiency and speed of operation in grading peas and corn. In addition, the unitary construction of the unit provides for utmost portability and requires a minimum amount of floor area; and all of the parts are readily accessible for inspection, cleaning or repair. The suspension means for the successive screens provides for oscillation of these screens in a most simple manner, and such oscillatory motion most effectively advances the product along the inclined path provided by the screens while permitting and aiding gravitation of the product through the screen openings; and the wiper blades of resilient material which wipe across the bottom of each screen perpendicular to the oscillatory motion thereof most effectively aid in keeping the screen mesh open without crushing or otherwise damaging the product. As hereinabove indicated, a single common motor may be used for driving both the shaft 12 and the camshaft 20 if desired, but in such event, a suitable reduction in the drive should be provided for the cam shaft 20.

It should be understood that it is not desired or intended to limit this invention to the exact details of construction herein shown and described, since various modifications within the scope of the appended claims may occur to persons skilled in the art to which this invention pertains.

I claim:

1. In a screen type separator for bulk granular material, a main frame, a series of vertically spaced superimposed and longitudinally inclined parallel screen decks of different mesh normally confined within said frame, parallel suspension links connecting the opposite upper and lower ends of each deck with said frame for arcuate oscillatory movement of the decks in the direction of their inclination, a primary series of eccentrics journaled on said frame at one end of said deck series for rotation about an upright axis, a driving connection between each of said eccentrics and the adjacent deck, an open frame member movably mounted between adjacent screen decks, a series of laterally spaced parallel wiper blades carried by each of said members and coacting with the bottom of the adjacent screen deck throughout its entire length, a secondary set of eccentrics journaled on said frame laterally of said decks for rotation about an upright axis, a driving connection between each of said secondary eccentrics and the adjacent blade carrying member, means for rotating said primary eccentrics to reciprocate the decks longitudinally of said wiper blades, and means for rotating said secondary eccentrics to cause said blades to travel laterally back and forth beneath the adjacent decks distances equal to the spacing of the blades from each other.
2. In a screen type separator for bulk granular material, a main frame, a series of vertically spaced superimposed and longitudinally inclined parallel screen decks of different mesh normally confined within said frame, parallel suspension links connecting the opposite upper and lower ends of each deck with said frame for arcuate oscillatory movement of the decks in the direction of their inclination, a primary series of eccentrics journaled on said frame at one end of said deck series for rotation about an upright axis, a driving connection between each of said eccentrics and the adjacent deck, fixed rods spanning said frame between and transversely of said decks,

an open frame member movably mounted upon each set of said fixed rods, a series of laterally spaced parallel wiper blades carried by each of said members and coacting with the bottom of the adjacent screen deck throughout its entire length, a secondary set of eccentrics journaled on said frame laterally of said decks for rotation about an upright axis, a driving connection between each of said secondary eccentrics and the adjacent blade carrying member, means for rotating said primary eccentrics to simultaneously reciprocate the decks longitudinally of 10 said wiper blades, and means for rotating said secondary eccentrics to cause said blades to simultaneously travel back and forth laterally beneath the adjacent decks distances equal to the spacing of the blades from each other.
